UNITED STATES PATENT OFFICE

FRANK A. TASCHNER, OF DETROIT, MICHIGAN

FIRE KINDLER

Application filed October 27, 1927, Serial No. 228,984. Renewed September 18, 1929.

This invention relates to gas burners, and more particularly to burners adapted and designed to be placed under the grate of a furnace, open fireplace or the like, for the purpose of starting a fire after sufficient fuel is spread on the grate, or for rekindling a fire that has burned low or entirely gone out.

One of the objects of this invention is to provide a gas burner giving a flame of sufficient volume and heat to directly ignite coal, coke or other combustible fuel spread over the grate or firebox of a furnace, without the use of preliminary combustibles such as paper, wood, charcoal or the like.

Another object is to provide a gas burner with a substantially right-angled passageway in the neck portion of the base threaded to receive a nozzle at one extremity of the passageway, and a gas flow pipe at the other extremity of the passageway also serving as a handle for moving the burner.

A further object is the provision of a gas burner with circumferentially spaced apertures in the upper portion of the base for the inflow of air, a cylindrical casing threaded into the upper portion of the base surrounding the upper extremity of the nozzle and forming a mixing chamber for the gas and air, a metallic coil adapted to be secured in the interior of the casing for substantially its full length, and a second coil interiorly of the other coil whereby the gas and air within the mixing chamber will be whirled with a spiral effect to the upper extremity of the casing, thus allowing a more thorough mixture of the gas and air within the mixing chamber and increasing the volume and intensity of the flame as it leaves the upper extremity of the casing.

Other objects and advantages will be apparent from the following description in which reference is made to the accompanying drawings showing a preferred embodiment of my invention and wherein similar reference numerals designate similar parts throughout the several views.

In the drawings:

Figure 1 is a side elevation of a furnace with parts broken away showing my im-

proved gas burner in position under a furnace grate.

Figure 2 is an enlarged detail sectional view taken substantially on the line 2-2 of Figure 3.

Figure 3 is an enlarged front elevation of the burner.

Figure 4 is an enlarged detail sectional view of the base taken substantially on the line 4-4 of Figure 2.

Figure 5 is a horizontal section of the upper portion of the base taken substantially on the line 5-5 of Figure 2.

Referring now to the drawings, the numeral 5 designates a furnace of the usual type for heating dwellings, stores, or the like, with a grate 6 secured in any desired manner at the bottom of the firebox and above the floor 6a. The numeral 7 designates combustible fuel such as coal, coke or the like which is spread over the upper surface of the grate 6 through the main door 8, in the usual or any desired manner.

It is to be understood that my improved fire kindler is adapted for use with any type of furnace or stove where the combustible fuel burned therein consists of coal, coke or the like, and no attempt has been made herein to show a complete furnace, the embodiment illustrated in Figure 1 being merely for the purpose of exemplification.

My improved burner 9 is to be placed on the furnace floor or support therein at a sufficient distance below the grate to allow the flames 26 to spread over a substantial portion of the coals 7. A gas flow pipe 10 of rigid material extends from the burner 9 through the opened draft door 25 and is connected to a gas jet or other source of supply (not shown) by means of a hose 11 made of rubber composition or other suitable material. The pipe 10 is of sufficient length to enable placing the burner wherever desired below the grate, this pipe also serving as a handle for inserting and withdrawing the burner.

My improved burner 9 comprises a base 28, preferably cast in one piece from white metal, bronze or other suitable material, and has a circular lower portion 12 shaped sub-

stantially as an inverted saucer of sufficient diameter to support the upper portions of the burner, and preferably formed with a plurality of circumferentially spaced apertures therein to lighten the weight; a reduced neck portion 13 and a substantially hollow cylindrical upper portion 14, flanged at its upper extremity to receive a casing 16, substantially as shown at 15.

10 The neck portion 13 of the base 28 is provided with a substantially right-angled passageway 17 extending from the side wall of the neck, substantially parallel with the lower portion 12 of the base 28, and then extending substantially vertically through the lower extremity of the upper portion 14 of the base. The passageway 17 is threaded at each extremity, one end receiving the gas flow pipe 10, substantially as shown at 18, and the other extremity receiving a nozzle 19, substantially as shown at 20.

15 The upper portion 14 of the base 28 is provided with a plurality of circumferentially spaced apertures 22 to permit an inflow of air 25 to the mixing chamber 30 as will be herein-after more thoroughly explained.

20 The nozzle 19 is preferably a hollow tubular member tapered at its upper extremity as shown at 21 and extending above the upper 25 extremity of the upper portion 14 of the base 28, and its lower extremity is adapted to be threaded into one extremity of the passageway 17.

25 The casing 16 is substantially cylindrical in shape, and its lower extremity is adapted to be threaded into the upper extremity of the upper portion 14 of the base 28 and completely surrounds the upper extremity of the nozzle 19, forming a mixing chamber 30 40 wherein gas reaching the chamber 30 through the flow pipe 10, the passageway 17 and the nozzle 19, is thoroughly mixed with air admitted through the apertures 22 in the upper portion 14 of the base.

45 A metallic coil herein shown as a coil spring 23 is adapted to be secured within the casing 16 and preferably extends the entire length of the casing. A second metallic coil is arranged interiorly of the lower portion 50 of the coil 23 and with its convolutions reversely arranged relatively thereto. One end of the second coil 24 is adapted to be stretched over the upper extremity of the nozzle 19; being held thereon and free from 55 the outer spring 23 by virtue of its resiliency.

55 The operation of my improved gas burner is believed to be apparent. Gas is admitted through the hose 11, pipe 10, passageway 17 and nozzle 19, into the mixing chamber 30 60 within the casing 16. Air entering through the apertures 22 is mixed with the gas within the chamber 30 and the mixture, by virtue of the coils 23 and 24 is forced to climb the casing 16 with a spiral effect, thus allowing 65 sufficient time for thorough mixing. When

the air and gas is ignited, the flame flares upwardly and outwardly from the upper extremity of the casing 16. It has been found that such flames will reach a sufficient height and are of sufficient volume and intensity to directly ignite coal, coke or like combustibles within a few minutes and without the aid of paper, wood, charcoal or like highly combustible material placed below the coal or coke in the manner now universally employed. Much time and expense may accordingly be saved by using my improved gas burner. Also the coil springs 23 and 24 will gradually become hot from exposure to the flames and their heat will serve to preliminarily heat the incoming air and gas within the combustion chamber 30.

70 While it will be apparent that the illustrated embodiment of my invention herein disclosed is well calculated to adequately fulfill the objects and advantages primarily stated, it is to be understood that the invention is susceptible to variation, modification and change within the spirit and scope of the subjoined claims.

75 90 What I claim is:

1. A gas burner comprising a base, a flow pipe removably secured to the base, a nozzle carried by the base, a casing removably secured to the base and surrounding the upper extremity of the nozzle, a coil mounted within the casing and a second coil mounted on the nozzle interiorly of the first mentioned coil.

wall surrounding the nozzle, a casing removably secured upon the base above the apertured wall and in spaced relation to the nozzle, and means for retarding the flow of gas from the nozzle and air from said apertured wall, comprising a pair of spaced metallic coils, one of which is supported by the casing and the other of which is supported solely by the nozzle, the convolutions of said coils being oppositely arranged.

10 In witness whereof I hereunto set my hand.
FRANK A. TASCHNER.
